UNITED STATES PATENT OFFICE.

DAVID L. DOBSON, OF MADISON, WISCONSIN, AND MABLE SLATER, OF MODESTO, CALIFORNIA.

POCKET.

1,202,683.

Specification of Letters Patent. Patented Oct. 24, 1916.

Application filed November 6, 1915. Serial No. 60,042.

To all whom it may concern:

Be it known that we, DAVID L. DOBSON and MABLE SLATER, citizens of the United States, residing at Madison, in the county of Dane and State of Wisconsin, and Modesto, in the county of Stanislaus and State of California, respectively, have invented new and useful Improvements in Pockets, of which the following is a specification.

10 The invention relates to article carriers, and more particularly to the class of pockets.

The primary object of the invention is the provision of a pocket wherein letters, cards, medicine, toilet and other small articles such as are usually kept for convenient access can be carried within the pocket.

Another object of the invention is the provision of a pocket of this character wherein the construction thereof is novel in form to 20 assure lightness in weight, compactness, rigidity, sanitation, strength, and also which will have a neat appearance and is convenient for access to the articles contained therein.

25 A further object of the invention is the provision of a pocket of this character which can be positioned so as to stand upon a table, and also is of a size to permit it to be placed within a suitcase, trunk, valise, sample or 30 other carrying case.

A still further object of the invention is the provision of a pocket of this character which is extremely simple in construction, thoroughly reliable and efficient in its 35 purpose, and inexpensive in manufacture.

With these and other objects in view, the invention consists in the construction, combination and arrangement of parts as will be hereinafter fully described, illustrated in 40 the accompanying drawings, and pointed out in the claims hereunto appended.

In the drawings:—Figure 1 is a plan view of a pocket constructed in accordance with the invention. Fig. 2 is a similar view looking toward the rear side thereof. Fig. 3 is a sectional view on the line 3—3 of Fig. 1. Fig. 4 is a sectional view on the line 4—4 of Fig. 1. Fig. 5 is an edge elevation. Fig. 6 is a sectional view on the line 6—6 of Fig. 1. Fig. 7 is a fragmentary perspective view 50 showing the pocket supported upon a rest.

Similar reference characters indicate corresponding parts throughout the several views in the drawings.

55 Referring to the drawing in detail, the

pocket comprises a rectangular shaped frame 10, preferably made from a single strand of stiff wire supporting a flexible body 11, preferably made from fabric, having a marginal casement 12 in which is received the frame 60 10, and upon one side of this body 11 is stitched or otherwise secured a section 13, preferably made from fabric, and is divided into a plurality of pockets 14 by means of stitching 15 separating the pockets from 65 each other, the section 13 at one edge being free and is formed with a casement 16 through which is passed a resilient web 17, the same being fixed at opposite ends thereof to the frame, and this web is designed to 70 close the mouths of the pockets 14, yet the pockets can be expanded to permit the insertion of articles therein.

Formed at the upper edge of the body 11 is a flexible closure flap 18 having provided 75 in its free corners buttonholes 19 through which are passed buttons 20 mounted on the free ends of elastic strips or webs 21, the opposite ends of which are suitably fixed to the body 11 near the lower corners thereof, and 80 when these buttons 20 are engaged in the buttonholes 19 the flexible webs 21 are stretched to hold the flap in stretched condition for closing the pockets 14 to prevent the falling of the articles therefrom when 85 contained therein.

Mounted upon the frame 10 at opposite ends thereof are clip-like members 22 formed with guide sleeves 23 in which are slidably fitted rods 24 each provided at one end with 90 an eye 25, while the rods at the opposite ends are formed with right-angular arms 26 and hook-like bights 27 at the point of junction of the arms 26 with the said rods, these bights 27 embracing the ends of the frame, 95 while the arms 26 are adapted to normally lie against the rear side of the body 11 on the frame, and to these arms is connected an elastic member 28 which holds the arms in this position, yet on passing the member 28 100 over the bottom edge of the frame 10 and inserting the same in the bights 27 the arms will be thrown at right angles to the frame so that the same may be supported in perpendicular position when brought at rest 105 upon a table or other support.

Connected to the eyes 25 on the upper ends of the rods 24 is a rope-like handle 29 whereby the device can be carried in the hand.

The device can be hung upon the wall or 110

placed upon a table, dresser or other support, and convenient access may be had to the pockets 14 on the freeing of the flap 18. Also this device can be placed within a 5 dress suit case, trunk, valise, or other traveling case, and the articles when held therein will be compact and readily accessible.

The rope-like handle 29 is looped so that it will hold the pocket in a balanced position 10 when hung upon the wall. This is of advantage when the articles in one end of the pocket are heavier than those in the other end and assures convenient access to the contents when the pocket is hung upon the wall.

15 From the foregoing description, taken in connection with the accompanying drawings, the construction and manner of use of the device will be clearly understood, and therefore a more extended explanation has 20 been omitted.

What is claimed is:—

1. A pocket structure comprising a frame, a flexible body fixed to the frame and held taut, a flexible section mounted on one side 25 of the body and stitched at intervals to form a plurality of cells, a resilient member at the free edge of the section and connected with the frame to normally hold the cells closed, and a cover flap connected with the 30 body to overhang the said section.

2. A pocket structure comprising a frame, a flexible body fixed to the frame and held taut, a flexible section mounted on one side 35 of the body and stitched at intervals to form a plurality of cells, a resilient member at the free edge of the section and connected with the frame to normally hold the cells closed, a cover flap connected with the body 40 to overhang the said section, the said cover flap being formed with buttonholes in its free corners, and resilient members carried by the body and detachably engageable in the buttonholes to hold the flap in closed position.

45 3. A pocket structure comprising a frame, a flexible body fixed to the frame and held taut, a flexible section mounted on one side of the body and stitched at intervals to form a plurality of cells, a resilient member at

the free edge of the section and connected 50 with the frame to normally hold the cells closed, a cover flap connected with the body to overhang the said section, the said cover flap being formed with buttonholes in its free corners, resilient members carried by 55 the body and detachably engageable in the buttonholes to hold the flap in closed position, clips mounted at opposite ends of the frame, rods slidable in said clips and having arms at right angles thereto, and a resilient 60 connection between the arms and adapted to be passed over the frame to hold the arms at right angles thereto.

4. A pocket structure comprising a frame, a flexible body fixed to the frame and held 65 taut, a flexible section mounted on one side of the body and stitched at intervals to form a plurality of cells, a resilient member at the free edge of the section and connected with the frame to normally hold the cells 70 closed, a cover flap connected with the body to overhang the said section, the said cover flap being formed with buttonholes in its free corners, resilient members carried by the body and detachably engageable in the 75 buttonholes to hold the flap in closed position, clips mounted at opposite ends of the frame, rods slidable in said clips and having arms at right angles thereto, a resilient connection between the arms and adapted to 80 be passed over the frame to hold the arms at right angles thereto, and hook portions bent from the rods at the point of juncture of the arms therewith and embracing the 85 ends of the frame and adapted to receive the resilient member when passed from one side of the frame to the other.

In testimony whereof we affix our signatures in presence of two witnesses.

DAVID L. DOBSON.
MABLE SLATER.
